UNITED STATES PATENT OFFICE

CHARLES E. LINEBARGER, OF CHICAGO, ILLINOIS

HYDROMETER

Application filed May 14, 1927. Serial No. 191,293.

This invention relates to hydrometers and particularly to means for testing the density of liquids contained in vessels, such as ordinary storage batteries. Although the various illustrations of the application to the invention which are described herein relate to storage batteries, yet it is to be understood that applications of the invention to many other containers could be made. One object 10 of the invention is to provide a very simple and convenient means for determining the densities of electrolytes in batteries and at the same time for determining the height of the electrolyte in the container. The device 15 thus indicates the condition of the electrolyte as to charge and also as to the need for distilled water.

Of the accompanying drawings Fig. 1 is an elevation partly in section of a device 20 which embodies the features of my invention; Fig. 2 is an enlarged detailed view of one of the elements for suspending the hydrometer; and Figs. 3, 4 and 5 are elevations of modified forms of the device.

25 In general the preferred application of my invention is to combine the testing element 10 with the vent plug or cap 11 of a storage battery 9 so that, when the cap is removed, the testing element will be removed with the cap and, at a glance, the condition of the battery will be indicated, both as to the degree of charge and the elevation of the level of the electrolyte.

The testing element or tube 10 is supported by the cap in any suitable manner, such as by means of the ordinary detachable baffle disk 13, and by the use of the supporting element 14. The disk is supported by friction in the bore of the cap. The supporting element is formed of any suitable material, such as celluloid, preferably being more or less resilient, and is adapted to have the end 15 passed into the upper end of the hydrometer tube with the loop thereon so formed as to press against the sides of the tube and support the tube by friction at the proper elevation. The other end of the element is attached to the plug in any suitable manner. I prefer to slip it over the baffle disk as indicated, the descending

portion passing through the recess 16 which is provided, in such baffles, for the purpose of forming a vent for escaping gases. Also, in order to prevent the tube from inadvertently slipping off from the supporting 55 element I provide an inwardly projecting flange 17 on the upper end of the tube against which the upper end of the loop will strike and thus prevent the tube from passing off of the loop. 60

When so suspended the tube can be adjusted as to its elevation, as the resiliency of the loop will hold it in any adjustable position; and it may be set so as to reach downwardly into the liquid substantially to the 65 upper edge of the plates. Any suitable hydrometer may be used; but I prefer the one indicated which comprises the tube 10 with the lower end closed and preferably enlarged, as indicated. An opening 18 is 70 formed a short distance above the lower end of the tube. In the tube are placed one or more hydrometric units. These are preferably what are called in the trade "Chaslyn balls" which have a density slightly less than 75 the density of the liquid when fully charged, so that the balls will float on the liquid in the bulb when the tube is removed from the battery, providing the battery is sufficiently charged; and the elevation of the liquid in 80 the bulb will indicate the elevation of the liquid in the container with reference to the plates.

It will thus be seen that I have provided means which may be very conveniently used 85 for determining the amount of charge of the battery and also the amount of distilled water, if any, that is needed to replace the evaporated water. Any inspection of an ordinary storage battery in an opaque container requires the removal of the vent cap, and with my device, this operation is all that is necessary in order to fully determine the condition of the battery as the hydrometer is removed with the cap and may be easily inspected. 90

In Fig. 3 I illustrate a modified form of the device consisting of a tube 20 having an elbow 21, with an opening 22 at the elbow. 95 This form of tube is preferable in some cases, 100

and the weight of the arm 23 tends to tilt the tube somewhat and cause more friction between the tube and the suspending element 24 so as to insure holding the tube in its adjusted position.

Fig. 4 illustrates a modified form of the suspending element. This element or hook 25 has corrugations on the suspending arm which coact with the lip 26 in the tube, and hold the tube more firmly in its adjusted position.

Fig. 5 shows a further modification in which the loop 28 of the tube is forced down into the bulb 29 for the maximum elevation of the tube. The tube, however, may be lowered and held in adjusted positions by friction of the loop and tube.

I claim as my invention:

1. In a storage battery a vent plug in combination with a hydrometer, said plug having a detachable plate mounted therein, and friction means for adjustably suspending said hydrometer from said plate.

2. In a storage battery a vent plug in combination with a hydrometer, said plug having a detachable plate mounted therein, and suspending means comprising a resilient strip adapted to be connected to said plate and to be resiliently and slidably connected to said hydrometer.

3. In a storage battery a vent plug in combination with a hydrometer, said plug having a detachable plate mounted therein, said hydrometer being suspended for adjustable elevations on said plate, said hydrometer having a tubular open end, suspending means fixed to said plate with one end projecting into said tubular end, and resilient means fixed to said end and tending to press against the sides of the tubular member.

4. In a container for holding liquids, a vent cap, a hydrometer, a hook for supporting said hydrometer, and means associated with said cap for supporting said hook, said hook being adapted to be hooked onto said means.

5. In a container for holding liquids, a vent cap, a supporting element associated with said cap, a strip bent to form a hook on each end, said strip being adapted to be detachably hooked onto said supporting element by one hook, and a hydrometer supported by the other hook on said strip.

6. In a container for holding liquids, a vent cap, a supporting element attached to said cap, a hydrometer support, said support comprising a vertical strip of celluloid bent to form a hook on one end, and having the other end bent and passing into and supporting said hydrometer, said hook being adapted to be hooked onto said element.

7. In a container for holding liquids, a vent cap, a supporting element attached to said cap, a hydrometer support adapted to be detachably hooked onto said element, said

hydrometer having one end tubular, said support comprising a strip of resilient material having a hook on each end, one end being hooked onto said element and the other end passing into said tubular end, and being hooked onto said hydrometer.

8. In a container for holding liquids, a vent cap, a supporting element attached to said cap, a hydrometer support, a hydrometer fixed to said support, said hydrometer having one end tubular, said support comprising a strip of resilient material having a hook on each end, one end being adapted to be hooked onto said element, and said hydrometer having a flange in said end onto which the other end of said strip is hooked.

In testimony whereof, I hereunto set my hand.

CHARLES E. LINEBARGER.
